CLAIM

The ornamental design for a mount for a component of a photovoltaic assembly as shown and described.

DESCRIPTION

FIG. 1 is a rear elevation view of a mount for a component of a photovoltaic assembly provided in a position of use relative to the component and a frame of the photovoltaic assembly;

FIG. 2 is a front, top perspective view of the mount;

FIG. 3 is a front, bottom perspective view of the mount;

FIG. 4 is a front elevation view of the mount;
FIG. 5 is a rear elevation view of the mount;
FIG. 6 is a right elevation view of the mount;
FIG. 7 is a left elevation view of the mount;
FIG. 8 is a top plan view of the mount; and,
FIG. 9 is a bottom plan view of the mount.

The dash-dash broken lines depict portions of the mount that form no part of the claimed design. The broken lines showing a component of a photovoltaic assembly, a frame of the photovoltaic assembly, and a threaded fastener in FIG. 1 depict environmental subject matter only and form no part of the claimed design.
